UNITED STATES PATENT OFFICE.

URI H. BROWN, OF ZANESVILLE, OHIO, ASSIGNOR TO BROWN MANUFACTURING COMPANY, OF ZANESVILLE, OHIO, A CORPORATION OF OHIO.

CULTIVATOR.

SPECIFICATION forming part of Letters Patent No. 755,214, dated March 22, 1904.

Application filed March 13, 1903. Serial No. 147,597. (No model.)

To all whom it may concern:

Be it known that I, URI H. BROWN, a citizen of the United States, residing at Zanesville, in the county of Muskingum and State of Ohio, have invented certain new and useful Improvements in Cultivators, of which the following is a specification, reference being had to the accompanying drawings.

My invention relates to cultivators, and particularly to riding-cultivators which are provided with an arched axle, so that they straddle the rows of corn and cultivate upon each side thereof; and its main object is to provide new and improved means by which the cultivator-beams may be swung laterally to one side or the other by the foot of the driver, either simultaneously—both moving toward one side or the other together—or separately, each being moved independently of the other in order to guide the cultivator-blades properly around any irregularities in the corn.

It has for a further object the providing of a new and improved yoke by which the cultivator-beams may be connected so as to swing laterally together, but which may be separated in such a way that either beam may swing laterally independently of the other and by the adjustment of which the distance between the cultivator-beams from side to side may be varied and set at different distances apart.

In the accompanying drawings, Figure 1 is a side elevation. Fig. 2 is a rear elevation. Fig. 3 is a top or plan view of the cultivator-beams and the means by which they are laterally swung. Fig. 4 is an enlarged detail showing the mechanism employed when the beams are to be separately swung laterally. Fig. 5 is enlarged detail showing the lower end of the yoke which connects the cultivator-beams and its connection with the cultivator-beams. Fig. 6 is an enlarged detail, being a view, partially in section, of the foot-lever and its pivot, showing its method of support upon the cultivator-beam. Fig. 7 is an enlarged detail, being a section on line 7-7 of Fig. 2. Fig. 8 is an enlarged detail, being a

top view of the top portion of the yoke connecting the cultivator-beams; and Fig. 9 is an enlarged detail, being a rear view of the side parts of the yoke connecting the cultivator-beams, showing the cultivator-beams in cross-section.

Referring to the drawings, 10 indicates an arched axle. 11 indicates wheels journaled upon the outer ends of the said arched axle.

12 indicates a seat-beam supported from the arched axle 10 and carrying a seat 13.

14 indicates the top frame of the cultivator carried upon the axle 10, and upon which the usual hand-levers 15, rack-bars 16, and connecting devices are mounted. As these hand-levers, rack-bars, and connecting devices for the lifting of the cultivator-beams may be of any well-known and approved form and description and form no part of my present invention, it is believed that it is unnecessary to describe them more fully here.

17 indicates the front arch of the cultivator, which is carried upon the frame 14 and supports pipe-boxes 18 upon its outwardly-turned ends, which are of the usual form and construction and form no part of my present invention.

19 indicates the tongue of the cultivator. 75

20 21 indicate cultivator-beams, which are connected with the pipe-boxes 18 by means of the usual yokes 22 23. These yokes are of the usual form and description and are constructed in the well-known way to permit the cultivator-beams to swing both vertically, so as to raise them from the ground, and laterally or from side to side.

24 25 indicate pivots, which, as best shown in Fig. 6, are conical in shape and are secured in an upright position upon suitable supports 26, fastened to the cultivator-beams 20 21.

27 indicates foot-levers provided with stirrups 28 and having a long arm 29, a short arm 30, and a bearing or socket 31. The bearing or socket 31 is bored centrally in a conical shape to fit over and turn upon the pivot 24. The pivot 24 and bearing or socket 31 are conical in shape in order to take up wear.

By making the pivots 24 25 conical in shape and of suitable height and by providing the foot-levers 27 with sockets 31, bored centrally in a conical shape to fit over the pivots 24 25, the levers are also given a firm support, so that they may not only be used in swinging the cultivator-arms laterally, as hereinafter described, but also to force the cultivator-shovels into the ground when the levers are 10 pressed by the foot of the operator.

32 indicates bolts, which are screwed upon the top of the pivots 24 in order to secure the levers 27 in place.

33 indicates links, the rear end of each of 15 which is pivoted in the short arm 30 of the levers 27 and the other end pivotally connected with lugs 34, carried upon the outwardly-projecting ends of the arch 17.

The lugs 34 are adjustably secured upon the 20 outwardly-projecting ends of the arch 17 in such a way that they may be slid in and out thereon and secured in any desired position. By this means an adjustable connection is secured by means of which the cultivator-beams 25 may be spread apart or brought somewhat more closely together and held in the desired position.

35 36 indicate bent levers, which are pivoted in lugs 37 38 upon each side of the frame 30 14. The lower ends of the levers 35 36 pass through bearings 39 40, mounted upon the outsides of the cultivator-beams 20 21 and swiveled thereto, as best shown in Fig. 9. The bearings 39 40 are so constructed that 35 they may slide up and down upon the lower straight ends of the levers 35 36 as the cultivator-beams are raised or lowered.

Referring to Figs. 7 and 8, 41 42 indicate bars which are pivotally connected, respectively, with the upper ends of the bent levers 35 36. 43 indicates a clip which is secured to the outer end of the bar 41 and embraces the bar 42. 44 indicates a clip which is secured to the outer end of the bar 42 and embraces the bar 41. The bars 41 42 near their central portions are slotted, as is shown in Fig. 7, and are secured at any desired adjustment, sliding upon one another in the clips by means of a bolt 45 and a wheel-nut 46. It is obvious that when the 50 wheel-nut 46 is loosened the cultivator-beams may be spread apart or brought together, rocking the levers 35 36 on their pivots either toward or away from each other at their lower ends and moving their upper ends correspondingly either away from or toward each other, the bars 41 42 sliding in the clips 43 44, whereby the distance between the cultivator-beams may be adjusted and when the desired adjustment is reached may be locked in position by 55 screwing home the wheel-nut 46. When thus held together, it is obvious that either cultivator-beam or both may be raised or lowered, the bearings 39 40 sliding on the lower ends

of the levers 35 36. It is also obvious that if either cultivator-beam is swung laterally the 65 other one will be swung in the same direction. For instance, if cultivator-beam 20 is swung toward its adjacent wheel the lower end of the lever 35 will be swung in the same direction, the upper end of the lever 35 will be swung inward, carrying the upper end of the lever 36 in the same direction and swinging the lower end toward the center of the machine, carrying with it cultivator-beam 21 and moving it in the same direction and the same distance as cultivator-beam 20. In other words, the beams 75 will be swung in unison. This swinging is accomplished by means of the foot-levers above described.

In case it is desired by the driver to swing 80 the beams to the right the lever 27, which is connected with the cultivator-beam 21, is pushed forward by the foot of the driver resting in the stirrup 28. This, as is indicated by dotted lines in Fig. 3, will swing the cultivator-beam 21 to the right of the driver, and by the action of the levers 35 36 with the beams the other cultivator-beam 20 will be swung in 85 the same direction into the position shown in dotted lines in Fig. 3, the foot-lever 27 connected with the beam 21, being swung backward, as is shown by dotted lines in said figure. When it is desired to return the cultivator-beams to their original position, the foot-lever 27 connected with the beam 20 is 95 pushed forward until the beams assume their original position. In case the cultivator-beams are to be swung to the left of the driver the foot-lever 27 mounted upon the beam 20 is 100 swung forward, when the reverse of the movements above described takes place. In case it is desired that the beams should not swing simultaneously, but that they should be laterally swung together, the wheel-nut 46 and bolt 45 are removed and the bars 41 42 105 allowed to either slide freely upon each other or to slide out of their clips entirely and allowed to hang idle. In this case either beam can be moved outward toward the adjacent wheel by thrusting forward the foot-lever connected with said beam. In this case, however, the swinging of one beam will not swing the other, and consequently the pushing forward of the opposite foot-lever will not return the beams to their original position. 110

Referring to Fig. 4, 47 indicates a retractile spring which is secured at one end to a suitable lug 48 on each of the cultivator-beams 20 21 and connected at its other end with the short arms 30 of the levers 27. This spring, 115 which is used only when the top portion of the connected yoke is disengaged, serves by its contraction to return the cultivator-beams to their original position after having been swung outwardly by the forward movement 120 of the foot-lever.

While I have said that my improvements apply particularly to a riding-cultivator and have shown and described them in such a cultivator, it is obvious that the yoke by which the beams are connected could be used equally well with the walking-cultivator and that handles of the usual form could be attached to the cultivator-beams for such purpose.

It will be seen that by constructing the separable yoke which connects the cultivator-beams as above described—that is to say, by having its side levers pivoted to the cultivator-frame and the upper ends of said levers projecting above the frame—the cross-bars which connect the top of the yoke are sufficiently high above the frame to clear the corn, and at the same time an unobstructed view of the corn can be had by the driver sitting on the seat between the sides of the yoke and below the cross-bars as the machine is driven in the field. The cross-bars also by reason of their height form a convenient rest for the lines.

That which I claim as my invention, and desire to secure by Letters Patent, is—

1. In a cultivator, the combination with an arch and a shovel-beam carried on said arch and adapted to swing laterally and vertically thereon, of a lever pivoted on said shovel-beam, a clip mounted on said arch and laterally adjustable thereon, and a link connected at its rear end with one arm of said lever and at its forward end with said clip, substantially as described.

2. In a cultivator, the combination with an arch having outward-projecting ends, shovel-beams carried on said arch and adapted to swing vertically and laterally thereon, of levers pivoted on said shovel-beams, clips mounted on said projecting ends and laterally adjustable thereon, and links connected at their rear ends with said levers and at their forward ends with said clips, substantially as described.

3. In a cultivator, the combination with an arch, shovel-beams carried on said arch and adapted to swing laterally and vertically thereon, of conical pivots mounted on said beams, foot-levers having bearings conically bored to rotatably support said levers on said pivots, and links connected at their forward ends with said arch and at their rear ends with said levers, substantially as described.

4. In a cultivator, the combination with an arch, and shovel-beams carried by said arch and adapted to swing vertically and laterally thereon, of levers pivoted on said shovel-beams, links connected at their forward ends with said arch, to one side of the forward ends of said shovel-beams, and at their rear ends with one arm of said levers, and a yoke connecting said shovel-beams, substantially as described.

5. In a cultivator, the combination with an

arch, and shovel-beams carried by said arch and adapted to swing vertically and laterally thereon, of levers pivoted on said shovel-beams, links connected at their forward ends with said arch to one side of the forward ends of said shovel-beams and at their rear ends with one arm of said levers, and a separable yoke connecting said shovel-beams, substantially as described.

6. In a cultivator, the combination with a frame, an arch carried by said frame, and shovel-beams carried on said arch and adapted to be swung vertically and laterally, of levers pivoted on said shovel-beams, links connected at their forward ends with said arch to one side of the forward end of said shovel-beams and at the rear ends with one arm of said levers, and a separable yoke pivotally mounted on said cultivator-frame and connecting said shovel-beams, substantially as described.

7. In a cultivator, the combination with a frame, an arch carried by said frame, and shovel-beams carried on said arch and adapted to be swung vertically and laterally, of levers pivoted on said shovel-beams, links connected at their forward ends with said arch to one side of the forward ends of said shovel-beams and at the rear ends with one arm of said levers, levers pivoted on said frame and slidably connected at their lower ends with said shovel-beams and having their upper ends projecting above said frame, cross-bars pivoted to the upper ends of said levers, and means for detachably and adjustably securing said cross-bars together, substantially as described.

8. In a cultivator, the combination with a frame, shovel-beams carried by said frame and adapted to swing vertically and laterally, and means for swinging said beams laterally, of levers pivoted on said shovel-beams, links connected at their forward ends with said arch to one side of the forward ends of said shovel-beams and at the rear ends with one arm of said levers, levers pivoted on said frame and slidably connected at their lower ends with said shovel-beams and having their upper ends projecting above said frame, cross-bars pivoted to the upper ends of said levers, and means for detachably and adjustably securing said cross-bars together, substantially as described.

9. In a cultivator, the combination with a frame, and a shovel-beam carried by said frame and adapted to swing laterally, of a lever pivoted on said shovel-beam, a link connected at its forward end with said frame to one side of said shovel-beam and at its rear end with one arm of said lever, and a spring connected with the said arm of said lever and with said shovel-beam, substantially as described.

10. In a cultivator, the combination with an arch, and a shovel-beam mounted on said arch and adapted to swing vertically and laterally thereon, of a lever pivoted on said shovel-beam, a link connected at its forward end with

said lever and with said shovel-beam forward of the pivotal point of said lever, substantially as described.
